UNITED STATES PATENT OFFICE.

GERALD SWALLOW, OF BRIDGEPORT, PENNSYLVANIA, ASSIGNOR TO DIAMOND STATE FIBRE COMPANY, OF BRIDGEPORT, PENNSYLVANIA, A CORPORATION OF DELAWARE.

INSULATION OF CONTACT RAILS OF ELECTRIC RAILWAYS.

Application filed March 30, 1926. Serial No. 98,589.

The principal object of the invention is to provide an improved insulator for electric conductor rails or "third" rails as commonly used on some classes of electric railways. 5 These rails are usually near the track level or the ground level and are ordinarily a source of danger to workmen, to passengers and to the general public.

The object of the invention is to provide a 10 simple and inexpensive insulator which can extend longitudinally throughout the entire length of the rails or throughout such portions of the length as may be selected. In accordance with one phase of the present invention I provide an insulator adapted to fully protect the sides of the rail, that is, all 15 except the contact surface thereof. In accordance with another phase of the invention I provide an insulator formed with longitudinally extending parallel sections and having suitable means for connecting the sections.

In the accompanying drawings I have shown various embodiments of the invention 20 in order that the character thereof may be clear, but it is to be understood that the drawings are not to be construed as defining or limiting the scope of the invention, the claims forming a part of this specification 25 being relied upon for that purpose.

Of the drawings:

Figure 1 is a side view of a section of conductor rail provided with an insulator embodying the invention;

30 Figs. 2 to 6 are cross-sectional views showing different embodiments of the invention adapted for covering the bottom and one side of a rail of T cross-section;

35 Figs. 7 to 11 are cross-sectional views showing other embodiments of the invention adapted to cover the bottom and both sides of a rail of T cross-section;

40 Figs. 12 to 15 are cross-sectional views showing different forms of insulators embodying the invention and adapted to be used with rails of the so-called "umbrella" cross-section; and

45 Figs. 16 and 17 are cross-sectional views showing different insulators embodying the invention and adapted to be used with a rail of the so-called "dumb-bell" cross-section.

50 Referring to Fig. 1 of the drawings, 1 represents a conductor rail and 2 represents one of the series of supporting and insulat-

ing brackets on which the rail is supported. 55 The rail 1 is shown as being of "dumb-bell" cross-section but any usual or preferred section may be used, the form of the supporting bracket being changed to correspond. As illustrated the bracket comprises a 60 standard 2^a, an insulator 2^b of porcelain or other suitable material, and a clamp 2^c. The rail itself and the supporting brackets therefor constitute no part of my present invention and will not therefore be described in further detail.

Figures 2 to 6 show insulators adapted to be used with conductor rails of the standard so-called T cross-section. The insulators shown in these figures are adapted to cover 70 only the bottom and one side of the rail, as for some classes of service this is all the protection that is required. The rail is shown and described as being in the upright position with the top surface thereof serving as 75 a contact surface adapted to be engaged by the contact shoes on the locomotives or cars. It will be understood, however, that the invention is not limited to the upright position of the rail and that without departing 80 from the spirit of the invention the rail may be mounted in inverted position or otherwise.

In accordance with the invention, the insulator is formed of vulcanized fibre in 85 sheet form and is bent or otherwise shaped to conform to all or a part of the cross-sectional outline of the rail. In order to facilitate manufacture of the insulator, I form it in two or more longitudinally extending 90 companion sections. These sections are preferably suitably joined and they are ordinarily joined by readily removable means which permit the sections to be connected together after they have been put in 95 place on the rail.

The insulator shown in Fig. 2 comprises two sections 3 and 4. The section 3 engages the upper outer portion of the rail flange at one side thereof and extends directly upward therefrom to cover the corresponding side of the rail head. The top contact surface of the rail is left exposed. The section 4 covers the bottom of the rail and is shaped to conform to the outer portion of 100 the rail flange at the opposite side thereof. The two sections 3 and 4 are provided with 105 downward extending edges forming a joint

at 5. These two edge portions are connected by means of bolts 6 and nuts 7, both preferably formed of hard or vulcanized fibre or other suitable insulating material. 5 It will be seen that the two sections 3 and 4 can be separately formed and can be conveniently assembled in final position on the rail. After assembly, they can be secured to each other and to the rail by means of 10 the bolts 6 and the nuts 7.

The construction shown in Fig. 3 comprises a section 8 which covers one side and the bottom of the rail and a section 9 which engages the upper outer portion of the rail flange for the purpose of holding the main section 8 in place. The two sections are provided with a horizontal joint at 10 and the edge portions of the two sections are held together with bolts and nuts such as already 20 described.

The construction shown in Fig. 4 is similar to that shown in Fig. 3, the parts 8^a and 9^a being similar respectively to the parts 8 and 9 except that the joint 10^a extends 25 downward instead of horizontally.

The construction shown in Fig. 5 is similar to that shown in Fig. 4 except that the joint 10^b between the sections 8^b and 9^b is at or near the center of the rail instead of 30 being at one side thereof.

In the construction shown in Fig. 6 there is a section 11 covering one side of the rail and a section 12 covering the bottom of the rail. A third section 13 is provided which 35 is similar to the section 9 shown in Fig. 3. The three sections 11, 12 and 13 are connected together by means of horizontal joints 14 and 15.

The construction shown in Figs. 7 to 40 11 differ essentially from the construction shown in Figs. 2 to 6 in that provision is made for protecting both sides of the rail including both sides of the head thereof. It will be seen that substantially all portions 45 of the rail are covered except the top contact surface.

The constructions shown in Fig. 7 includes two sections 16 and 17 which are shaped to conform to the respective upper 50 outer portions of the rail flange and which extend directly therefrom to cover the corresponding sides of the rail head. One of these sections, as for instance 17, is extended across the bottom of the rail and a vertical joint is provided at 18.

The construction shown in Figure 8 is similar to that shown in Figure 7 except that the sections 16^a and 17^a are connected by means of a horizontal joint 18^a.

60 The construction shown in Figure 9 is also similar to that shown in Fig. 7 except that the sections 16^b and 17^b are connected by a vertical joint 18^b which is located at or near the center of the rail instead of at one side thereof.

The construction shown in Figure 10 includes two sections 19 and 20 covering the two sides of the rail and a third section 21 covering the bottom thereof. These three sections are connected by means of horizontal joints 22, 22.

The construction shown in Figure 11 is similar to that shown in Figure 10 except that the sections 19^a, 20^a and 21^a are connected by vertical joints 22^a, 22^a. 75

In Figures 12 to 15 I have shown insulators adapted to be used with a rail of "umbrella" cross section. It will be observed that in each case the insulator covers substantially all portions of the rail surface 80 except the contact surface at the top.

In Figure 12 there are two sections 23 and 24 covering the two sides of the rail, and one of these sections, as for instance 24, is extended across the bottom thereof. The 85 two sections are joined by means of a vertical joint 25.

The construction shown in Figure 13 is similar to that shown in Figure 12 except that the sections 23^a and 24^a are connected 90 by means of a horizontal joint 25^a.

In Figure 14 I have shown an insulator comprising sections 26 and 27 covering the two sides of the rail and a section 28 covering the bottom of the rail. These sections 95 are connected by means of horizontal joints 29, 29.

The construction shown in Figure 15 is similar to that shown in Figure 14 except that the sections 26^a, 27^a and 28^a are connected by means of vertical joints 29^a. 100

In Figures 16 and 17 I have shown an insulator adapted for use with a rail of "dumb-bell" cross section, and as shown it is assumed that the contact surface thereof 105 is at the bottom.

Figure 16 shows an insulator comprising two similar sections 30 and 31 which are shaped to conform to the outline of the rail at the respective sides thereof. These two 110 sections are connected by means of a vertical joint 32 which is shown as being located at or near the center of the rail.

The construction shown in Figure 17 is similar to that shown in Figure 16 except 115 that a different type of joint is provided for the two sections 30^a and 31^a. As shown, there is a separate joint strip 33 which overlaps the two sections 30^a and 31^a, being connected thereto by means of bolts and nuts 120 such as have already been described.

What I claim is:

1. An insulator for an electric conductor rail of standard T cross-section, comprising sheet vulcanized fibre shaped to conform to the bottom and outer edges of the flange and to extend directly from the upper outer portions of the flange to cover the sides of the head while leaving the top surface exposed. 125

2. An insulator for an electric conductor 130

5 rail comprising a plurality of longitudinally extending companion sections of sheet vulcanized fibre shaped respectively to conform to different portions of the cross-sectional outline of the rail, and means for joining the sections to hold them in place on the rail.

10 3. An insulator for an electric conductor rail comprising a plurality of longitudinally extending companion sections of sheet vulcanized fibre shaped respectively to conform to different portions of the cross-sectional outline of the rail, and readily removable means for joining the sections to hold them in place on the rail.

15 4. An insulator for an electric conductor rail comprising a plurality of longitudinally extending companion sections of sheet vulcanized fibre shaped respectively to conform to different portions of the cross-sectional outline of the rail, and readily removable means formed of insulating material for

joining the sections to hold them in place on the rail.

5. An insulator for an electric conductor rail of standard T cross-section, comprising a plurality of longitudinally extending companion sections of sheet vulcanized fibre shaped respectively to conform to different portions of the cross-sectional outline of the rail, the said sections respectively extending directly from the upper outer portions of the flange to cover the sides of the head while leaving the top surface exposed.

10 6. An insulator for an electric conductor rail comprising a plurality of longitudinally extending companion sections of sheet insulating material shaped respectively to conform to different portions of the cross-sectional outline of the rail, and means for joining the sections to hold them in place upon the rail.

GERALD SWALLOW.
